UNITED STATES PATENT OFFICE.

DAVID M. BOWEN, OF LOS ANGELES, CALIFORNIA.

GAS HEATER.

Application filed July 25, 1927. Serial No. 208,221.

This invention relates to heaters of the type used for domestic heating purposes. While the invention may be adapted for burning any kind of fuel, it is intended particularly to be used for burning gas. The general object of the invention is to produce a heater of simple construction which can be very economically manufactured, and the elements of which are formed from flat plates; also to provide a heater of this type which will present a relatively large heating surface for transferring the heat from the gases of combustion to the air.

A further object of the invention is to provide a heater having a plurality of relatively narrow air flues disposed between relatively narrow gas flues, and also to provide simple means for directing the gases of combustion in a circuitous route through the heater.

One of the objects of the invention is to provide a heater composed of a plurality of heating elements of simple construction thereby enabling heaters of different capacity to be readily constructed simply by increasing the length; in other words, one of my objects is to produce a heater composed of a plurality of simple units, to facilitate the production of different sizes of heaters by simply increasing or decreasing the number of heating elements.

Further objects of the invention will appear hereinafter.

The invention consists in the novel parts and combination of parts to be described hereinafter, all of which contribute to produce an efficient gas heater.

A preferred embodiment of the invention is described in the following specification, while the broad scope of the invention is pointed out in the appended claims.

In the drawings:

Fig. 1 is a plan of a heater embodying my invention.

Fig. 2 is a vertical section through the heater taken on the line 2—2 of Fig. 1. This line is located on the center line of the heater extending in a front and rear direction.

Fig. 3 is a longitudinal vertical section through the heater taken about on the line 3—3 of Fig. 1.

According to my invention the heater is composed of a plurality of heating elements of simple construction. These elements include relatively flat plate like air ducts which are mounted parallel with each other in the heater and disposed slightly apart so as to

form gas flues between them. As the gases of combustion pass through the heater they are broken up into a great number of small, narrow currents which pass between the air flues, that is to say, between the flat plates which form the sides of the air flues. In this way a relatively large area of surface is provided through which the heat transfer takes place. The air flues are preferably constructed of thin plates of sheet metal through which the heat can be readily transferred.

In the following specification I have described the invention as embodied in a heater in which the elements are in the form of air ducts.

Referring to the drawing, 1 represents a casing which is preferably of substantially rectangular, or box, form. This casing may be conveniently constructed of thin metal plates, and includes a forward wall 2, a bottom plate 3, a cover plate 4 and a rear wall 5.

Within the casing I provide a plurality of air flues 6. These flues are elongated in horizontal cross section, preferably in a front and rear direction; in other words, each air flue is a flat, hollow, or tubular element with the two side plates 7 connected by a narrow front plate 8 and a narrow rear plate 9. Each air flue has an inlet opening 10 at its lower end, and an outlet opening 11 at its upper end. These heating elements or flues 6 are set up in the casing in a substantially parallel relation and the plates that form each flue are connected at their upper ends by seams 12 to the cover plate 4 (see Fig. 3). In this way relatively narrow gas flues 13 are formed between the adjacent air flues.

Within the casing, preferably near the front wall and near the bottom plate 3, I provide a burner 14 which may be a gas burner in the form of a tube extending horizontally along the front and interior of the heater. Access may be had to the burner to light it through a hinged door 15 in the front wall of the heater.

The rear wall 5 is provided with an outlet 16 for the gases of combustion. If desired the bottom plate 3 may be provided with air inlet openings, or draft openings 17 for the admission of sufficient air for combustion of the gas.

While the elements already described will produce an efficient heater I prefer to provide means within the heater for guiding the gases of combustion in a circuitous route as they pass from the burner 14 to the outlet 16.

I provide means for causing them to pass up at the front and downwardly toward the rear in a single pass composed of a plurality of currents between the air flues. In order to 5 accomplish this I prefer to provide baffle-plates extending up or down from the bottom plate 3 or the cover plate 4. In the present instance I provide a front baffle-plate 17^a that extends up from the bottom plate 3 10 near the forward wall 8 of the air flues, and the upper edge of this baffle-plate is disposed at a considerable distance below the cover plate 4 of the heater so that an opening 18 is formed at its upper edge through which 15 the gases of combustion can pass readily into the gas flues 13 between the air flues. A similar baffle-plate 19 is provided at the rear of the air flues and mounted in a similar manner extending down from the cover plate 4 20 and terminating short of the bottom plate 3 so that an opening 20 is formed through which the gases may pass to the outlet chamber 21 at the back of the heater and with which the outer opening 16 communicates. 25 The burner is located in a combustion chamber 22 formed between the baffle-plate 17^a and the front wall 2 of the heater. I prefer to have the air ducts 6 relatively narrow at the lower ends and relatively wide 30 at their upper ends, (see Fig. 2). This enables the baffle-plate 17^a to be disposed in an inclined direction over the burner so that the gases of combustion move upwardly under the inclined plate thereby realizing a condition which favors the transfer of heat from 35 the gases to the air currents that pass up through the heater. This tapered form of the air flues also enables the baffle-plate 19 to be disposed in an inclined position. With 40 this form for the air ducts it should be evident that the combustion chamber 22 contracts in a horizontal direction towards the upper end and the outlet chamber 21 does likewise. The arrows indicate the course of the 45 gases and air in passing through the heater. It is understood that the embodiment of the invention described herein is only one of the many embodiments this invention may take, and I do not wish to be limited in the 50 practice of the invention, nor in the claims, to the particular embodiment set forth.

What I claim is:—

1. In a heater for burning gas or the like, the combination of a substantially rectangular casing having a bottom wall and a cover wall, a plurality of air flues of horizontally elongated cross section within said casing, each air flue having an inlet opening for the air at the said bottom wall and an outlet opening for the air at the said cover wall, a burner within the casing near the bottom wall, said air flues being disposed apart so as to form gas flues between the same, a baffle-plate within the casing extending up

from the bottom wall for guiding the gases of combustion upwardly so as to cause the same to enter the gas flues at an elevated point in the casing, and a second baffle-plate extending downwardly from the cover wall near the rear wall of the casing, operating to produce 70 a downward pass of the gases of combustion through the gas-flues. 65

2. In a heater for burning gas or the like, the combination of a casing, a burner mounted in the lower portion of the casing near the forward wall thereof, a plurality of air flues of elongated horizontal cross section disposed within the casing in a front-and-rear substantially vertical plane, open at their upper and lower ends to conduct the air to 80 be heated through the heater, a baffle-plate extending upwardly within the casing on the forward ends of the said air flues and co-operating with the forward wall of the heater to conduct the gases of combustion upwardly 85 to an elevated point in the heater between the said air flues, said casing having a cover wall co-operating with the said baffle-plate to produce a downward pass of the gases of combustion toward the bottom of the heater, 90 a second baffle-plate extending downwardly from the cover wall of the casing adjacent to the rear ends of the air flues and co-operating with the back wall of the casing to produce an outlet chamber for the gases of combustion from the heater. 95

3. In a heater for burning gas or the like, the combination of a substantially rectangular casing having a bottom plate and a cover plate, a burner mounted in the lower portion 100 of the casing, a plurality of air-flues of elongated horizontal cross section disposed substantially parallel with each other within the casing and spaced apart so as to form gas flues between the air flues and under the cover plate, the forward walls of said air flues being disposed in an inclined position over 105 said burner, and an outlet in the rear wall of the casing for the gases of combustion. 105

4. In a heater for burning gas or the like, 110 the combination of a substantially rectangular casing having a bottom plate and a cover plate, a burner extending along the interior of the casing adjacent the said bottom plate, a plurality of air flues of elongated horizontal cross section disposed substantially parallel with each other in the casing and spaced apart from each other to form gas flues through which the gases of combustion may pass toward the rear wall of the casing, 115 an outlet for the gases of combustion at the rear wall, and baffle-plates at the front and rear sides of the air flues for guiding the gases of combustion in a circuitous route in passing from the burner to the outlet. 120 125

Signed at Los Angeles, Calif., this 19th day of July, 1927.

DAVID M. BOWEN.
